UNITED STATES PATENT OFFICE.

ALFRED ROZOWSKY, OF BROOKLYN, NEW YORK.

CANDY PACKAGE.

Application filed May 21, 1923. Serial No. 640,631.

To all whom it may concern:

Be it known that ALFRED ROZOWSKY, citizen of the United States, residing at New York city, in the county of Kings and State 5 of New York, has invented certain new and useful Improvements in Candy Packages, of which the following is a specification.

This invention relates to folding boxes or cartons, and more particularly to that 10 class of boxes or cartons designed as an economical container for candy and other articles offered for sale.

One object of the invention is to provide an attractive box or carton which may be 15 sold to children as a candy package containing candies and toys, and which shall simulate the appearance of an automobile.

A further object is to provide a box or 20 carton which is made from a single blank of paper, card-board or other suitable material which can be packed and stored in a small space, and when desired for use, can be easily folded and assembled by any 25 one of average intelligence, not requiring skilled labor.

Other objects of this invention will in part be obvious and in part hereinafter pointed out.

The invention accordingly consists in the 30 features of construction, combinations of elements and arrangement of parts which will be exemplified in the construction hereinafter described and of which the scope of application will be indicated in the following claims.

In the accompanying drawings, in which is shown one of various possible illustrative embodiments of this invention,—

Fig. 1 is a plan view of a blank from 40 which my improved box or carton is made;

Figs. 2, 3, and 4 are perspective views showing the steps of folding the blank in the formation of the box or carton; and

Fig. 5 is a view in transverse section on line 5—5 of Fig. 4.

Referring to the drawings, A represents the blank from which the box or carton is made. This blank A is cut or stamped from the desired stock and all parts thereof hereinafter described are preferably, although 50 not essentially, integral.

The blank A comprises four main parts in alignment, namely a side 1, a back 2, a side 3, and a front 4, divided by transverse fold lines 5, 6 and 7 respectively. A bottom 55 8 is integral with the side 1, is separated

therefrom by a plurality of curved cuts 9 with fold lines 10 at the ends of the cuts 9 in alignment with the edge of side 3, and curved supporting members 11 are formed 60 at the edge of side 3 corresponding to like members 12 formed by the cuts 9, so that said members 11 simulate wheels and function as supports for the box or carton when set up.

A securing tongue 12 is formed at the edge of bottom 8 and a fold line 13 made at the juncture of the bottom and the tongue. Integral tabs 14 are formed at both edges of the back 2 and have fold 70 lines 15 at their lines of juncture with the back.

A closure flap 16 constituting the box top is formed at one edge of side 3 and provided with a securing tongue 17 and fold 75 lines 18 and 19 respectively are provided at the lines of juncture of the tongue 17, flap 16 and side 3.

The front 4 is made at opposite edges with tabs 20 and 21 respectively, both being preferably relatively long and having fold lines 22 and 23 respectively at their lines of juncture with the front 4. The tab 20 is divided by two parallel fold lines 24 and 25 respectively, so that the end portion 26 85 of the tab 20 constitutes a securing tongue while the intermediate sections 27 and 28 form covering sections to simulate the wind shield and hood top respectively, as indicated most clearly in Figs. 3 and 4.

The side portions 1 and 3 at their extremities and at one edge have each two cuts 29 and 30 respectively to form two tongues 31 and 32. The tongues 31 have inclined fold lines 33 and the cuts 34 are at an angle to 95 give the desired hood shape. One of the tongues 32 forms a part of tab section 28 and the other tongue 32 is integral with a tongue 34 on the end of side 1. This tongue 34 has a fold line 35 at its line of 100 juncture with side 1 and a second fold line 35 in registry with cut 30, and is adapted to be secured by adhesive to the front 4 and tab section 28, the adhesive being either on the tongue 34 or the front 4 and tab section 28 whereby these parts can be secured together as one of the first steps in the folding operation.

The several fold lines are preferably scored or otherwise impressed to render the 110 folding accurate and easy and in shaping the box or carton the folding operation is

as follows: The blank A is folded on the lines 35, 5, 6, and 7 and the front 4 secured to half of tongue 34 by adhesive as shown in Fig. 2. The tongues 31 and 32 are folded inwardly and the tab section 28 secured by adhesive to the other half of tongue 34, while the tongue 26 is folded inside of the open top of the carton and the cover tab 16 secured in closed position over the tab 14 by projecting the tongue 17 into the box or carton, as shown in Fig. 3. The bottom 8 is then folded against the inwardly folded tabs 21 and 14 and secured by its tongue 12 so that the completed box or carton will appear as shown in Fig. 4 with the members 11 simulating wheels functioning as supports therefor, and the device as a whole having the appearance of an automobile.

Such a device readily lends itself for display purposes and is not only pleasing to the eye, but affords a convenient receptacle for candy and other contents offered for sale.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. As a new article of manufacture, a box or carton comprising sides, back, front, top and bottom cut from a single sheet of material arranged to form a totally enclosed receptacle body, said body having a reduced end portion and supporting means constructed to simulate in appearance a hood and wheels respectively of an automobile. 45

2. As a new article of manufacture, a box or carton composed of a single folded blank which when folded forms a totally enclosed receptacle having a reduced end and supporting portions to simulate in appearance 50 a hood and wheels respectively of an automobile.

3. A box or carton composed of a single integral blank comprising sides, back, front, bottom and top or closure portions all connected by fold lines, tabs on the back and front, tongues on one side portion and on the top and bottom portions, a pair of angularly disposed tongues cut from one edge and forward extremity of each side whereby 55 one end of the box or carton will be reduced in area when folded to simulate an automobile hood, and rounded supports cut from the bottom and provided on one side to simulate wheels. 60

In testimony whereof I affix my signature.

ALFRED ROZOWSKY.
